UNITED STATES PATENT OFFICE.

WILLIAM EVERETT VER PLANCK, OF SCHENECTADY, NEW YORK, ASSIGNOR TO GENERAL ELECTRIC COMPANY, A CORPORATION OF NEW YORK.

INTERNAL-COMBUSTION ENGINE.

Application filed November 5, 1919. Serial No. 335,846.

To all whom it may concern:

Be it known that I, WILLIAM E. VER PLANCK, a citizen of the United States, residing at Schenectady, in the county of Schenectady, State of New York, have invented certain new and useful Improvements in Internal-Combustion Engines, of which the following is a specification.

The present invention relates to internal combustion engines of the type in which the fuel is sprayed by fuel injectors directly into the combustion chamber either with or without the aid of compressed air and particularly to such engines wherein a plurality of injectors usually two, are provided which are arranged diametrically opposite each other and discharge conical sprays of fuel which impinge on each other.

The object of my invention is to provide an improved form of combustion chamber and arrangement of injectors in connection therewith and for a consideration of what I believe to be novel and my invention, attention is directed to the accompanying description and the claims appended thereto.

In the drawing, Fig. 1 is a vertical sectional view of an engine cylinder embodying my invention; Fig. 2 is a sectional view taken on line 2—2. Fig. 1, and Fig. 3 is a sectional view taken at a right angle to that of Fig. 1.

Referring to the drawing, 5 indicates a cylinder of an internal combustion engine having a cooling jacket 6; 7 indicates the cylinder head, and 8 a piston which moves in cylinder 5. In cylinder head 7 are inlet and exhaust valves 9 and 10 actuated by a rocking lever 11.

Now, according to my invention, I provide a combustion chamber in the head of the general form of a sphere on diametrically opposite sides of which are superimposed cones. The cones have the same axis and the sphere is of such diameter that the inner surfaces of the cones are tangent to its inner walls. By the term tangent to its inner walls, it will be understood that I do not intend to limit myself to exact tangency but only to tangency within ordinary limits. At the apex of each cone is located a spray nozzle of suitable design which discharges cone-shaped fuel sprays toward the sphere where they strike each other. The cones are of such size that they are slightly larger than the conical sprays of fuel dis-

charged from the nozzles so the fuel does not strike the sides of the cones. As a result the fuel sprays will strike each other at about the central vertical transverse plane of the sphere. The fuel sprays after they have impinged on each other will accordingly have the sphere to expand in which provides the maximum of space with the minimum wall surface.

In an engine of this type it is desirable that the combustion chamber communicate with the cylinder space through an opening of less diameter than the cylinder diameter. To this end I provide in the piston head a spherical depression which forms a part of the sphere of the combustion chamber and this depression is chosen of such size as to give the desired area of opening between the combustion chamber and cylinder while at the same time preserving the spherical outline of the combustion chamber. The arrangement is such that the suction and discharge valves are arranged on the surface of the sphere and preferably the opening between the combustion chamber and cylinder space is such that the valve seats may be machined and the valve removed through the same. This avoids the use of a two piece head.

On account of the high compression required in this type of engine the permissible size of combustion chamber is limited, and by my invention I so dispose this limited volume of combustion chamber that there will be no dead air pockets and that the fuel sprays can distribute fuel throughout the whole of the air in the combustion chamber. At the same time the arrangement is such that reasonable sized valves can be used.

In the drawing, 15 indicates the spherical portion of the combustion chamber and 16 and 17 the two cones superimposed thereon. In the present instance the sphere is shown as being of such diameter that it is larger than a sphere tangent to the sides of the cone. 18 indicates the spherical depression in the head of piston 8 and 19, the opening between the combustion chamber and the cylinder space.

In the present instance, two opposed spray nozzles are shown but as is obvious more than two may be used if found desirable.

The arrangement of the combustion chamber is suitable for either two cycle or four

cycle engines and for engines operating on either the Otto cycle where the fuel is injected ahead of the dead center to allow time for complete vaporization so that at 5 dead center a uniform explosive mixture is made, or on the high compression cycle where the fuel is injected near the dead center and burns as it is admitted.

With the above described arrangement I 10 obtain a shape of combustion chamber which conforms very closely to the form of the sprays and which gives a complete and uniform mixture of the fuel with the air in the combustion chamber. At the same time, the 15 combustion chamber comes within the permissible limits in size.

In accordance with the provisions of the patent statutes, I have described the principle of operation of my invention, together with the apparatus which I now believe to represent the best embodiment thereof, but I desire to have it understood that the apparatus shown is only illustrative and that the invention may be carried out by 25 other means.

What I claim as new and desire to secure by Letters Patent of the United States, is:

1. In an internal combustion engine, walls forming a combustion chamber having the 30 contour of a sphere upon which are superimposed a plurality of opposed cones, the inner surfaces of the cones being tangent to the inner walls of the sphere.

2. In an internal combustion engine, walls forming a combustion chamber having the 35 contour of a sphere upon which are superimposed a plurality of opposed cones, and fuel injectors located at the apices of said cones which discharge conical shaped sprays toward said sphere and each other, the in-

ner surfaces of said cones being tangent to the inner walls of the sphere whereby the fuel sprays from the injectors will be distributed throughout the combustion chamber.

45

3. In an internal combustion engine, the combination of a cylinder, a piston therein, walls forming a combustion chamber of the contour of a sphere upon which is superimposed two diametrically opposed cones, a portion of said sphere being formed by a depression in the top of the piston of such size as to provide a passage of restricted area between the combustion chamber and the cylinder, and fuel-injecting means at the apices of said cones, the inner surfaces of said cones being tangent to the inner walls of the sphere whereby the fuel sprays from the injector will be distributed throughout the combustion chamber.

60

4. In an internal combustion engine, the combination of a cylinder, a piston therein, walls forming a combustion chamber of the contour of a sphere upon which is superimposed two diametrically opposed cones the inner surfaces of which are tangent to the inner walls of the sphere, a portion of said sphere being formed by a depression in the top of the piston of such size as to provide a passage of restricted area between the combustion chamber and the cylinder, fuel injecting means at the apices of said cones, and suction and discharge valves resting on the upper half of the wall of said sphere, said valves being accessible through said 65 70 75 passages.

In witness whereof, I have hereunto set my hand, this 4th day of November, 1919.

WILLIAM EVERETT VER PLANCK.
